UNITED STATES PATENT OFFICE.

DANIEL H. TALBERT, CLAUDE SHAW, JAMES I. HOLCOMB, AND JACOB F. HOKE, JR.,
OF INDIANAPOLIS, INDIANA, ASSIGNEES TO THE AMERICAN BOX BALL COMPANY,
OF INDIANAPOLIS, INDIANA, A CORPORATION.

BOWLING APPARATUS.

1,035,658.

Specification of Letters Patent. Patented Aug. 13, 1912.

Application filed June 3, 1909. Serial No. 499,855.

To all whom it may concern:

Be it known that we, DANIEL H. TALBERT, CLAUDE SHAW, JAMES I. HOLCOMB, and JACOB F. HOKE, Jr., of Indianapolis, county 5 of Marion, and State of Indiana, have invented a certain new and useful Bowling Apparatus; and we do hereby declare that the following is a full, clear, and exact description thereof, reference being had to the 10 accompanying drawings, in which like letters refer to like parts.

The object of this invention is to provide a game apparatus which is provided with alley pins similar in appearance and location to the pins of ordinary bowling alleys. In other words, this device is a small bowling alley with the pins mounted on a frame instead of being loose and independent of everything, as in ordinary bowling alleys.

20 In carrying out said invention the frame is so arranged that the alley pins will be positioned as in ordinary bowling alleys, and yet each of them is pivotally connected with said frame so as to be independently actuated by a rolling ball, and when actuated, turns from a vertical to a horizontal position and is held in that horizontal position until reset. All of the pins which have 25 been actuated are simultaneously reset or returned to a vertical position. The resetting is effected by means of a hand lever located at the front end of the apparatus.

In view of the force with which the balls will be thrown in such apparatus, the back 35 thereof is mounted so as to be yielding and the bottom arranged so the ball will roll from the back down into the return trough.

The full nature of this invention will be understood from the following description 40 and claims and the accompanying drawings.

Figure 1 is a side elevation of the apparatus centrally broken away and showing a ball after it has been thrown. Fig. 2 is a side elevation of a portion of the means for 45 resetting the pins, showing the same in normal position. Fig. 3 is the same after it has been actuated. Fig. 4 is a plan view of the rear end of the apparatus or alley, the forward portion being broken away. Fig. 50 5 is a plan view of the same with the pins and resetting means and associated parts removed. Fig. 6 is a vertical section of Fig. 4, the actuated end of the buffer plate at the back being shown by dotted lines.

Fig. 7 is a plan view of a portion of the pin 55 resetting means. Fig. 8 is a section on the line 8—8 of Fig. 7 showing the parts in their normal position. Fig. 9 is the same showing the actuating position thereof. Fig. 10 shows a portion of Fig. 6 on a large scale 60 the normal position of the alley pin being shown by full lines, and the actuated position of the pin being shown by dotted lines. Fig. 11 is a side elevation of a forward pin 65 in its actuated position. Fig. 12 is a plan view of what appears in Fig. 11.

The ball course, alley or platform 15, over which the balls 16 are rolled, is mounted upon legs 17 elevated above the floor and has the usual side troughs 18. The return 70 trough 19 is located below the alley 15 and inclined from the rear to the front. At the front end of the alley there is a post 20 and a resetting lever 21 pivoted thereto which resets the mechanism at the rear through 75 the instrumentality of the connecting rod 22 and means hereafter explained.

The alley pins 25 are formed like ordinary bowling alley pins excepting that the lower rear half thereof is cut away to enable them to operate as hereafter explained. 80 They are pivoted on pins 26 in ears 27 connected with cross bars 28 that are connected with lateral bars 29, the bars 28 and 29 forming a substantially A-shaped frame 85 with the rear end of said frame at each side fastened to the post 50, and the front end secured and held in place by bars 131 secured thereto and extending laterally and turned down and fastened to the sides of 90 the alley near the troughs 18. The alley pins are mounted on the lateral bars of the A-shaped frame so as to be in the same positions the alley pins usually occupy in ordinary bowling alleys, there being one 95 pin mounted on the front cross bar 28, two on the next cross bar to the rear, three on the third cross bar, and four on the fourth cross bar.

The alley pins 25 are pivoted near their 100 center of gravity, so that they are easy to operate, and are held vertical by a spring plate 31, which is secured to the rear upper surface of each pin, and its lower end bears against the rear edge of the plate 37 connected with the cross bar 28. Said spring plate 31 is held in place by a pair of guide plates 32 projecting rearwardly from each 105

alley pin and between which said spring plate operates. When a ball strikes an alley pin, it throws it to the horizontal position, and such movement of the pin moves the 5 spring plate 31 to the horizontal position, so that the notch 33 in the rear end thereof will receive and be engaged by the stop pin 34 in the rock shaft 35 extending transversely of the device, and mounted at one 10 end in bearing 36 connected with the rear cross bar 28, and at the other end in the post 50 secured to one side of the alley. Therefore, the pin 34 coöperating with the 15 spring plate 31 maintains the alley pin in its horizontal position.

The device is provided with buffers 38 secured to arms 39 and 40 connected with the cross bars 28. The upper ends of the alley pins strike on the buffers 38 on the arms 39 20 extending downwardly and rearwardly from the cross bars 28 in front of said pins, see Figs. 5 and 10, so that the buffers are on the upper side of said arms 39. The lower ends of all the alley pins mounted on the cross 25 bars 28 strike the buffers 38 on the under side of the arms 40 projecting forwardly from said cross bars 28. The ears 27 extend downwardly from the bars 28 so as to give the alley pins opportunity to move to the 30 horizontal positions without engaging the cross bars 28, and that is one reason why the rear lower portions of the alley pins are cut away.

The alley pins are returned to their vertical positions by actuating the lever 21 35 and rod 22. Said rod at its rear end is pivoted to the lower end of a lever 45, which is fulcrumed between its ends at 46 to the side of the alley 15. A connecting bar 47 40 connects the upper end of said lever 45 to the lower end of a crank 48, which is secured on the rear rock shaft 35. There are rock shafts 35 mounted in connection with each bar 28. The rear rock shaft 35 is the actuating rock shaft and power is transmitted to it originally from the lever 21, and from it power is transmitted to the arms 51 extending upwardly from each rock shaft 35 45 and connected by a bar 52. Each rock shaft 35 has a finger 54 which is located opposite each alley pin and normally extending rearwardly, so that when the rock shafts are operated, said alley pins will be turned to a vertical position, and the reverse operation 50 of the lever 21 will return the resetting means to the full line position shown in Fig. 10. The plate 37, as shown in Fig. 7, has a slot 69 in it to permit the operation of the pin 34. The cross bars 28, side bars 55 60 65 29, plates 37, buffer plates 39 and 40, and ears 27 are all formed integrally in one solid frame. The balls, after they have passed the alley pins, strike a buffer 60 suspended from the top 61 of the device at the rear end, see Fig. 6, which breaks the force of the

ball, and then the ball passes on and strikes the back 62, which is padded. This back is arranged so that it will yield rearwardly under the impact of the ball, it being slidably mounted on pins 63 at its upper ends 70 that extend rearwardly from the side wall 64 of the frame, and it is held from moving too far rearwardly by the spring 65 both at the top and the bottom, the inner ends of said springs being fastened to the top and 75 bottom, respectively, of the frame. The actuated position of said back 62 is indicated by dotted lines in Fig. 6. There is a straight pad 66 on each side wall of the structure at the rear end, and also a lower pad 67 arranged inclined downwardly toward the front so as to discharge the balls away forwardly from the back upon the end of the return trough 19.

What we claim as our invention and desire to secure by Letters Patent is:

1. An amusement apparatus of the kind described including a ball course, alley pins, means above the rear part of the ball course on which said alley pins are pivotally mounted in transverse rows with the lower ends normally extending downward to a point near the ball course and the alley pins in the adjacent rows being in staggered position relative to each other, means for stopping and holding said alley pins when moved by a ball one-fourth of a revolution, a longitudinally moving resetting bar beside the rows of alley pins, and means actuated by the movement of said resetting 100 bar for simultaneously resetting the alley pins which have been actuated.

2. An amusement apparatus of the kind described including a ball course, a transverse bar above the rear part of the ball course, ears extending forwardly and downwardly from said transverse bar, alley pins pivoted between their ends in said ears, a spring plate secured to the rear surface of the upper end of each pin that is frictionally 110 in engagement with the transverse bar for holding the pin normally vertical, and a releasable stop for engaging the rear end of said spring when the alley pin is in the horizontal position for holding it in that position until reset.

3. An amusement apparatus of the kind described including a ball course, a transverse bar above the rear part of the ball course, ears extending forwardly and downwardly from said transverse bar, alley pins pivoted between their ends in said ears, a spring plate secured to the rear surface of the upper end of each pin with a notch in the other end thereof, a guide mounted on 120 the pin engaging each side of said spring, a rock shaft mounted at the rear of said transverse bar, and a pin secured in said rock shaft behind each alley pin in position to engage the rear end of said spring 125 130

when the alley pin is in the horizontal position for holding it in that position.

4. An amusement apparatus of the kind described including a ball course, a plurality of transverse bars above the rear part of the ball course one in front of another, ears extending forwardly and downwardly from said transverse bars, alley pins pivoted between the ends of said ears, a spring plate 10 secured to the rear surface of the upper end of each alley pin, a rock shaft mounted behind and parallel with each transverse bar, a pin extending from said rock shaft adapted to engage the rear end of said spring 15 plate when the alley pin is moved to a horizontal position and hold it in that position, fingers extending rearwardly from said rock shaft in position to engage the lower part of the alley pins when the rock 20 shaft is actuated, and means for simultaneously actuating all of said rock shafts for releasing said alley pin holding means and returning the alley pins to their vertical positions.
- 25 5. An amusement apparatus of the kind described including a ball course, alley pins, means for pivotally mounting the alley pins over the rear part of said ball course in a vertical position so that when struck they will 30 be moved to a horizontal position, means for catching the upper ends of the alley pins

when turned to a horizontal position for holding them in that position, and means for releasing said holding means for all of the alley pins which have been struck. 35

6. An amusement apparatus of the kind described including a ball course, transverse bars over the rear portion of the ball course, pins pivotally mounted in a vertical position on said bars so as to be moved to a horizontal position when struck, means for catching said pins when struck to hold them in a horizontal position, a rock shaft mounted behind each cross bar, arms extending therefrom for engaging the alley pins and 40 returning them to their vertical position, arms extending upwardly from said rock shafts, means for releasing each of said catches, and a connecting rod extending from each of said arms to said releasing 45 means for operating the latter. 50

In witness whereof, we have hereunto affixed our signatures in the presence of the witnesses herein named.
